(57) **CLAIM**

The ornamental design for a U-bolt clamp, as shown and described.

DESCRIPTION

FIG. 1 is a perspective view of a U-bolt clamp, according to the present invention;

FIG. 2 is a front elevational view of the U-bolt clamp of FIG. 1; the rear elevational view being substantially identical thereto;

FIG. 3 is a right side view of the U-bolt clamp of FIG. 2; FIG. 4 is a left side view of the U-bolt clamp of FIG. 2; FIG. 5 is a top plan view of the U-bolt clamp of FIG. 2; and, FIG. 6 is a bottom plan view of the U-bolt clamp of FIG. 2. The surface(s) or portion(s) of the article not shown in the drawing or described in the specification form(s) no part of the claimed design.
